CHLORO CYANOBUTANES

Joy G. Lichty, Stow, Ohio, assignor to Wingfoot Corporation, Akron, Ohio, a corporation

No Drawing. Application May 7, 1943,
Serial No. 486,113

3 Claims. (Cl. 260—464)

1

This invention relates to certain chloro compounds and their preparation and, more particularly, to chloro cyanobutanes and a method of obtaining the same.

The pyrolysis of 2-cyano-2-acetoxybutane results in the production of three unsaturated compounds; namely, 1-methyl crotononitrile, cis and trans forms, and 1-ethyl acrylonitrile. The course of the pyrolysis may be indicated as follows @ 450—600° C.:

2

Example 1

From the pyrolyzate resulting from the pyrolysis of 2-cyano-2-acetoxybutane was taken 242 grams of a fraction boiling at 117°—138° C. This product consisted in the main of the cis and trans 1-methyl crotononitriles, but undoubtedly contained some 1-ethyl acrylonitrile. Chlorine was bubbled into the pyrolyzate fraction while cooling until the increase in weight was 179 grams. The theoretical increase in weight for the addition of one mol of chlorine at a temperature below 45° C. to one mol of the methyl crotononitrile is 212 grams. The addition product was then distilled and the following fractions obtained:

Fraction	Boiling point	Wt., g.	Per cent yield	Density	Ref. index
1	74° C./28 mm.	24.5			
2	74°—82° C./28 mm.	205.6	54	$D_{15}^{20}=1.161$	$N D^{20}=1.4508$
3	82° C./28 mm.—172° C./16 mm.	25.2			
4	172°—176° C./17 mm.	83.0	22	$D_{15}^{20}=1.251$	$N D^{20}=1.4964$

It has now been found that any one of these three unsaturated compounds, or the pyrolyzate containing both the cis and trans 1-methyl crotononitriles and also containing 1-ethyl acrylonitrile, may be chlorinated to add two atoms of chlorine to the double bond. The 1-methyl crotononitriles, both cis and trans forms, yield 1-methyl-1,2-dichlorobutyronitrile and the 1-ethyl acrylonitrile yields 1-(chloromethyl)-1-chlorbutyronitrile. The above-mentioned nitriles may alternatively be designated as 2-cyano butene-2 and 2-cyano butene-1, and the respective products, 2,3-dichloro 2-cyanobutane, and 1,2-di-

Fraction 2 is the 1-methyl-1,2-dichlorobutyronitrile or 2,3 dichloro 2-cyanobutane

while fraction 4 probably is the dimer of this compound.

Example 2

35 The method was also applied to the chlorination of 1-ethyl acrylonitrile. Here 162 grams of 1-ethyl acrylonitrile was chlorinated at a temperature of 45° C. or less until the increase in weight was slightly more than the theoretical. 40 Distillation gave the following fractions:

Fraction	Boiling point	Wt., g.	Per cent yield	Density	Ref. index
1	82° C./28 mm.	9.1			
2	82°—86° C./28 mm.	105.5	64	$D_{15}^{20}=1.192$	$N D^{20}=1.4539$
3	86°—120° C./28 mm.	31.6			
4	180°—190° C./28 mm.	38.0	12	$D_{15}^{20}=1.273$	$N D^{20}=1.5003$

chloro 2-cyanobutane. The reaction is indicated by the equation:

To illustrate the method of preparation, the following experiment was conducted, but it will be understood that the same is illustrative and that the invention is not limited to the details given.

In this instance, fraction 2 is 1-(chloromethyl)-1-chlorbutyronitrile or 1,2-dichloro 2-cyanobutane

and fraction 4 its dimer.

60 In carrying out the process the 2-cyanobutene,

such as the 1-methyl crotononitrile or the 1-ethyl acrylonitrile treated above, is cooled preferably to a temperature of 45° C. or even less, and chlorine is passed in until the increase in weight corresponds to the theoretical increase called for by the addition of one molecule of chlorine to a molecule of the butene. Of course, less chlorine may be passed in with consequent reduction in yield, but preferably an excess will be employed to insure as far as possible that all of the organic ingredient is utilized. The products may be separated by fractional distillation or other suitable means.

The dichloro 2-cyanobutanes are believed to be new compounds. The class includes the 2-chloro 2-cyanobutanes containing an additional chlorine radical, particularly those in which the chlorine radical is in one of the positions adjacent to the 2-position, e. g., 2,3-dichloro 2-cyanobutane and 1,2-dichloro 2-cyanobutane.

The chloro cyanobutanes are useful as intermediates in the preparation of polymerizable organic compounds, such as those obtainable by pyrolysis. They may also be useful as fumigants or insecticides.

While there have been described above certain preferred embodiments of the invention, it will be apparent to those skilled in the art that various modifications and changes may be made therein without departing from the spirit of the invention or the scope of the appended claims.

I claim:

1. The 2-chloro 2-cyanobutanes containing an additional chlorine radical in one of the positions adjacent to the 2-position.
 2. 2,3-dichloro 2-cyanobutane.
 3. 1,2-dichloro 2-cyanobutane.

JOY G. LICHTY.
